UNITED STATES PATENT OFFICE.

JAMES P. QUAM, OF MILWAUKEE, WISCONSIN, ASSIGNOR TO THE RICHARDSON-PHENIX CO., OF MILWAUKEE, WISCONSIN, A CORPORATION OF WISCONSIN.

LUBRICATOR.

1,173,382.

Specification of Letters Patent. Patented Feb. 29, 1916.

Application filed September 23, 1915. Serial No. 52,136.

To all whom it may concern:

Be it known that I, JAMES P. QUAM, a citizen of the United States, residing at Milwaukee, in the county of Milwaukee and 5 State of Wisconsin, have invented certain new and useful Improvements in Lubricators, of which the following is a specification, reference being had to the accompanying drawing, forming a part thereof.

10 This invention relates more particularly to lubricators for feeding a mixture of oil and powdered graphite to engine cylinders, pistons and valves and other bearings, and its main objects are to prevent precipitation 15 or settling of the graphite and to maintain an even mixture thereof with the oil in the reservoirs from which the lubricant is supplied to the bearings; to reduce the quantity of oil required for adequate lubrication; and 20 generally to increase the efficiency and improve the construction and operation of lubricators of this class.

It consists in the construction, arrangement and combination of parts as hereinabove particularly described and pointed out in the claims.

In the accompanying drawing similar characters designate similar parts in both figures.

30 Figure 1 is a vertical section of one kind of lubricator to which the invention is applicable and in which it is embodied; and Fig. 2 is a similar view of another kind of lubricator embodying the invention.

35 Although the invention is illustrated in connection with air spray lubricators specially designed for the lubrication of engine cylinders, pistons and valves, it is applicable to other kinds of lubricators for 40 various purposes.

Referring to Fig. 1, which shows the invention as embodied in a lubricator in which provision is made for compressing air to spray the lubricant as it is discharged therefrom, 1 designates the lubricant reservoir having a detachable top plate 2, which is formed with a filling opening and provided with a removable cover 3, for the opening, and a strainer 4.

50 A cam shaft 5, passing horizontally through the reservoir, is provided inside thereof with a number of cams 6, according to the size of the lubricator, and at one end outside of the reservoir, with the usual 55 means (not shown) of rotation. Attached

to and removable with the top plate 2, are a number of pairs of axially aligned barrels or cylinders 7 and 8, a pair for and in alignment with each cam 6. The barrels or cylinders 7, which are located below the cam 60 shaft 5, and the barrels or cylinders 8, which are located above it, are open at the ends directed toward the cam shaft, and are provided with pistons or plungers 9 and 10. The pistons or plungers are connected in 65 corresponding pairs with yokes 11, fitting over the cams 6.

The pump cylinders 7, which are supported and guided by one or more hangers or brackets 12, attached with the compressor cylinders 8, to the top plate 2, are adjustable axially toward and from the cam shaft, to vary the effective strokes of the plungers 9 and the quantity of lubricant forced thereby from the barrels 7. The barrels 7 are adjusted by means of screw rods 13, swiveled at their lower ends in plates 14, which are attached to the lower ends of the barrels and threaded adjacent to their lower ends in the hangers or brackets 12. These 70 rods extend upwardly parallel with the plungers 9 and 10 through the top plate 2, and are provided at their upper exposed ends with means such as knurled heads 15, 75 for turning them.

The barrels 7 are formed in opposite sides with inlet and outlet ports 16 and 17, and the plungers 9 are cut away or recessed for a portion of their length from their lower ends next to the outlet port 17, to permit 80 the lubricant to be ejected through said ports after the inlet ports 16 are closed by the plungers in their downward movement. The outlet ports 17 open into passages 18, which are provided with upwardly opening 85 spring seated check valves 19, and are connected by tubes 20 surrounding the rods 13, with drip nozzles 21, above the top plate 2. The nozzles 21 open into sight glasses 22, 90 communicating at their lower ends with chambers 23 below the top plate 2, and connected by passages 24 with the compressor barrels 8. The passages 24 are provided with check valves 25. The barrels 8 are provided below the passages 24 with stuffing 95 boxes and packing 26 for the plungers 10. At their upper ends the barrels 8 are provided with spring seated discharge valves 27.

The caps at the upper ends of the sight 110

glasses 22 are formed with air inlet openings 28.

The parts thus far enumerated and described belong to the lubricators of the kind illustrated, in which the present invention is incorporated, and no claim thereto *per se* is made.

For feeding the lubricant to an engine cylinder or the like, a feed pipe 29 is connected directly with the barrel 8 through the case of the discharge valve 27.

In the operation of the lubricator for feeding the lubricant, as the plungers 9 and 10 are moved upward by their actuating cams 6, lubricant is drawn from the reservoir 1 by the plunger 9 through the inlet port 16 into the lower end of the barrel, from which it is forced by the downward movement of the plunger through the outlet port 17, passage 18, past the check valve 19, thence upwardly through the tube 20, from the upper end of which it is discharged through the drip nozzle 21 into the sight feed glass 22 and chamber 23. With the downward movement of the plunger 10 the lubricant, with air admitted through the opening 28, is drawn through the passage 24 past the check valve 25, to the barrel 8. With the upward movement of the plunger 10, the air confined in the barrel 8 is compressed and discharged with the oil past the valve 27 into the feed pipe 29 and thence through a check valve and spray nozzle (not shown) into the engine cylinder or steam inlet pipe or passage thereof, the oil being sprayed by the compressed air discharged therewith as it passes the spring seated valve 27.

For the purpose of feeding powdered graphite with the oil to an engine cylinder or the like, or to any bearing requiring lubrication, it is necessary to keep the graphite in suspension and evenly distributed through the oil in the reservoir from which the lubricant is taken. The ordinary agitators such as spirals, paddles or other stirring devices, have been found ineffective and unsatisfactory for this purpose, since the graphite will gradually settle and adhere to such devices.

I have found that compressed air discharged in successive puffs into a reservoir containing oil and graphite, will overcome the difficulties and objections incident to the use of stirring devices of the character above mentioned, and will keep the graphite in suspension and thoroughly mixed and distributed throughout the oil.

The air may be compressed and discharged intermittently or in successive puffs, into the lubricator reservoir from which it is supplied to bearings of various kinds, in different ways. As shown in Fig. 1, one or more pipes 30, according to the size of the lubricator, are connected with the upper

ends of the compressor barrels 8, in the place of the oil spray feed pipes 29. Between each of the pipes 30 which lead downwardly through the top plate 2 into the lower part of the reservoir 1, and the discharge valve 27 of the compressor barrel 8 with which it is connected, a spring weighted valve 31, is inserted, and above this valve the pipe is provided with a three-way test cock 32, having a vent opening 33 to the atmosphere. The cock 32 is adapted in one position to open the vent 33 and close the pipe 30 between the vent and the reservoir, and thus affords means for observing and testing the air pressure produced by the plunger 10. In its normal position as shown, the cock 32 closes the vent 33 and opens the pipe 30, establishing and maintaining free communication between it and the chamber of the valve 31.

When a compressor barrel 8 is connected by a pipe 30 with the reservoir, as shown and described, for agitating the lubricant and keeping the graphite thoroughly mixed therewith, the associated pump barrel 7 is adjusted to supply only a sufficient amount of lubricant to the compressor plunger 10 to seal and adequately lubricate the same. This adjustment may be permanently made and the adjusting screw 13 may be omitted.

In the operation of the compressed air agitator as shown in Fig. 1, the air drawn by the downward movement of the upper plunger 10 into the barrel 8 through the air inlet 28, is compressed by the upward movement of the plunger, and passing the discharge valve 27 into the pipe connection between it and the valve 31, increases the pressure therein till it is sufficient to lift the valve 31 against the tension of its spring, which is quite stiff or strong. The valve 31 is thereupon suddenly and momentarily opened and the sudden increase of pressure thus produced in the pipe 30, causes a puff of air to be discharged therefrom into the lubricant in the lower part of the reservoir 1. This operation is repeated at frequent intervals and the lubricant is thus agitated and the graphite is kept thoroughly mixed with and evenly distributed throughout the oil, so that a proper mixture is constantly maintained in the reservoir 1, to be supplied as required through the feed connection or connections 29, to the bearings or parts to be lubricated. The lower plunger 9 used in connection with the agitator, supplies just enough lubricant to the upper air compressing plunger 10 to keep it sealed and well lubricated.

Where a supply or source of compressed air is available, it may be utilized in connection with a lubricator for keeping graphite mixed with oil, as shown in Fig. 2, in which 34 designates a pipe leading from a supply or source of compressed air into the chamber

of the spring weighted valve 31 above the valve seat. The pipe 30, which leads into the lower part of the reservoir 1, for agitating the lubricant contained therein, connects 5 with the valve chamber below the valve 31. A plunger 35, guided and provided with packing in the lower end of the valve case, is adapted to open the valve 31 against the tension of its spring for intermittently admitting 10 compressed air into the pipe 30. A rack 36, guided in a casing or body 37 in axial alinement with the plunger 35, meshes with a pinion 38 on a rocker shaft, which is provided with an arm 39, for connecting 15 it with an engine or other machine, and imparting an oscillatory movement to the pinion. An adjusting screw 40, threaded in the upper end of the rack 36 and fastened in adjusted position by a lock nut 41, affords 20 means for varying the lift or opening of the valve 31, and hence the quantity of compressed air admitted to the pipe 30 and the volume and strength of the air puffs discharged into the lubricant in the reservoir 1. 25 This form of lubricator is provided with force feed mechanism and connections (not shown) for taking the mixed lubricant from the reservoir 1 and delivering it to the cylinder of an engine or to the bearings of a machine with which the lubricator is connected.

The operation of the compressed air agitator in this form of lubricant is in effect the same as that shown in Fig. 1. With the oscillation of the pinion 38, the rack 36 is reciprocated, and in its upward movement thrusts the plunger 35 upward against the weighted ball valve 31, momentarily lifting it from its seat against the tension of its spring. A quantity of compressed air determined by the adjustment of the screw 40, is thus admitted to the pipe 30, causing a sudden puff of air to be discharged from its lower end into the lubricant contained in the 40 reservoir 1. As the rack 36 is moved downward out of engagement with the plunger 35, the plunger is forced by the compressed air back to its initial position, and the ball valve 31 is closed by its spring. These operations being repeated at frequent and regular intervals, the graphite is kept thoroughly mixed with and evenly distributed throughout the oil contained in the reservoir 1, from which it is drawn and delivered 45 as required by the feed mechanism and connection or connections to the parts or bearings to be lubricated.

The reservoir 1 of either of the lubricators shown, is supplied with lubricant by removing the cover 3 and pouring the oil and graphite through the strainer 4.

Various changes in the construction and arrangement of parts of the compressed air agitator mechanism as applied to or embodied in lubricators of different kinds for 65 different purposes, may be made without departure from the principle and scope of the invention as defined in the following claims.

I claim:

1. In a lubricator the combination of a 70 lubricant reservoir and means for delivering a gas such as air in successive puffs into a fluid lubricant contained in the reservoir.

2. In a lubricator the combination with a lubricant reservoir and means for feeding 75 lubricant therefrom to a bearing, of means for introducing a gas in successive puffs into a fluid lubricant contained in the reservoir.

3. In a lubricator the combination of a 80 lubricant reservoir, a compressed air conduit leading into said reservoir below the normal level of the lubricant therein, a weighted valve normally closing said conduit, and means for intermittently opening said valve. 85

4. In a lubricator the combination of a lubricant reservoir, a compressed air conduit leading into said reservoir, a compressor having a reciprocating plunger for forcing air through said conduit into lubricant 90 contained in the reservoir, and a weighted valve in said conduit opening toward the reservoir.

5. In a lubricator the combination of a 95 lubricant reservoir, a compressed air conduit opening into the lower part of the reservoir, a compressor having a reciprocating plunger for compressing and forcing air in successive puffs into lubricant contained in the reservoir, a weighted valve in said conduit opening toward the reservoir, and a pump connected with the compressor for supplying a limited quantity of lubricant thereto for lubricating and sealing its plunger. 100

6. In a lubricator the combination with a lubricant reservoir, a compressed air conduit leading into the reservoir, a weighted valve opening in said conduit toward the reservoir, means for successively opening said valve, and a test cock between said valve and the discharge end of the conduit having a vent to the atmosphere and adapted to open the vent and close the conduit between the vent and reservoir and to close 110 the vent and open the conduit.

In witness whereof I hereto affix my signature in presence of two witnesses.

JAMES P. QUAM.
